JOHN Y. HAMILTON, OF CLINTON, MASSACHUSETTS, ASSIGNOR TO GEORGE CROMPTON, OF WORCESTER, MASSACHUSETTS.

Letters Patent No. 61,535, dated January 29, 1867.

IMPROVEMENT IN SHUTTLES FOR NARROW-WARE LOOMS.

The Schedule referred to in these Letters Patent and making part of the same.

TO ALL WHOM IT MAY CONCERN:

Be it known that I, JOHN Y. HAMILTON, of Clinton, in the county of Worcester, and State of Massachusetts, have invented an Improvement in Shuttles for Narrow-Ware Looms; and I do hereby declare that the following, taken in connection with the drawings which accompany and form part of this specification, is a description of my invention sufficient to enable those skilled in the art to practise it.

The invention relates to the method of applying the purn in shuttles for narrow-ware looms, and consists in not only employing a spring to create tension upon the bobbin, but also in so hinging the purn that it may be swung out from the shuttle (without removal therefrom) for reception or change of the bobbin, and in applying a spring to such hinged purn to keep it normally in position.

The drawings represent a shuttle embodying the invention; *A* showing the same in plan; *B* a vertical section in line of the purn; *C* a vertical cross-section on line *xx*. *A* denotes the frame of the shuttle constructed in the ordinary manner; *b* the tension wire held up to the surface of the bobbin by a spring *c*; *d* the purn or spindle upon which the bobbin or spool is supported. Usually this purn is merely pressed into position, one end entering a bearing in one end of the shuttle and the other end being bent and pressed into a slot extending from the upper side of the shuttle; but the purn so applied is apt to work loose and to be accidentally thrown or drawn from the shuttle, the tension spring and the draught upon the thread both having a tendency to force or draw it from position. To remedy these defects, I hinge the purn *d* at one end to the shuttle, or so secure it that one end may be swung out from the shuttle while the other remains attached thereto; and in connection with such hinging I apply a spring, *e*, which counteracts any tendency of the tension spring to throw the purn from position and holds it firmly in place while the shuttle is being operated, so that it cannot work loose. The end secured to the shuttle is bent round, as seen at *f*, a recess being cut into the shuttle for reception of such end, and a piece, *g*, inserted in the outer part of the same, a pin, *h*, extending through the bent end for the purn to swing upon without permitting the bent end to be withdrawn. The other end slips into a slot, *i*, the spring *e* holding it therein, as will be readily understood. It will be obvious that this construction admits of a much readier application and removal of the spools and of their greater steadiness when in position than can be obtained in the common arrangement.

I claim, in connection with a device for creating tension upon the bobbin, the arrangement of the purn to swing and the application of the spring to keep the purn in normal position with respect to the shuttle, substantially as described.

JOHN Y. HAMILTON.
